UNITED STATES PATENT OFFICE.

HARRY A. KUCERA, OF PHILADELPHIA, PENNSYLVANIA.

BOTTLE-STOPPER.

1,099,059.

Specification of Letters Patent.

Patented June 2, 1914.

Application filed July 23, 1912. Serial No. 711,084.

To all whom it may concern:

Be it known that I, HARRY A. KUCERA, a citizen of the United States, residing in Philadelphia, Pennsylvania, have invented 5 certain improvements in Bottle-Stoppers, of which the following is a specification.

One object of my invention is to provide a novel and relatively simple form of bottle stopper having its parts so arranged as to 10 permit of the flow of successive small amounts of liquid from the bottle and to prevent flow of liquid in the opposite direction.

It is further desired to provide a bottle 15 stopper of the above noted type which shall be particularly adapted for use in connection with bottles designed to contain preparations for application to the scalp, the construction being such that the various parts 20 shall be convenient and inexpensive to manufacture as well as certain in action.

These objects and other advantageous ends, I secure as hereinafter set forth, reference being had to the accompanying drawings, in which—

Figure 1 is an enlarged vertical section of the upper portion of a bottle illustrating my invention as applied thereto; Figs. 2, 3 and 4 are side elevations of the valve seat structure, and spring forming parts of my 30 invention; Fig. 5 is a side elevation of the stopper shown in Fig. 1; Fig. 6 is a vertical section of the cage structure; Fig. 7 is a horizontal section on the line $a-a$, Fig. 1, 35 and Fig. 8 is a vertical section of a modified form of my invention.

In the above drawings, 1 represents a bottle whose mouth in the present instance is provided with an outwardly extended flange 40 2. Over said mouth of the bottle and inclosing the same together with certain parts hereinafter described, I mount a substantially conical casing 3, terminating at its apex in a tubular extension 4 provided with a relatively 45 restricted outlet passage 5 and designed for the reception of a cap 6.

Resting upon the top of the bottle is a valve seat structure having a substantially semi-cylindrical portion 7, extending downwardly into the bottle neck and formed with a flange 7^a turned over the flange 8^a of a valve guiding structure or cage 8, so that the two structures make a liquid proof joint and are held in place by the casing 3. The 50 downwardly extending part 7 is provided with a substantially conical hole and forms

a seat for a hollow conical valve 9 whose upper end extends into the cage structure 8 and is capable of forming a liquid tight joint with an annular seat 10 therein. 60

The main portion of the cage structure 8 as shown is substantially cylindrical with its upper end semi-spherical in form and provided with a central outlet 11 which like the passage 5 in the casing 3, is of a relatively small area of cross section. In the inner surface of the walls of the cage 8, I form a number of elongated grooves 12 extending from points beyond the seat 10 to the lower end or face of said cage; it being 70 noted that the body of the valve 9 is substantially cylindrical and has a sliding fit within the said cage; being normally held to its seat by a light spring 13. I preferably form the various parts 3, 7, 8 and 9 of 75 aluminum and in attaching the casing 3 to the neck of the bottle, I place a gasket 14 of suitable material under the bottle lip or flange and turn the lower edge of said casing over this gasket as shown in Fig. 1. 80

As the stopper forming my invention is particularly designed for use on bottles containing relatively thin liquid such as water or alcoholic solutions, a reciprocating jerky movement of the bottle when in the inverted position will cause the valve 9 to move away from the seat structure 7 against the action of the spring 13 so that the liquid is free to pass through the valve seat into the hollow interior of said structure 7, 85 thence through the side grooves 12 of the cage 8 and out of the restricted opening 11 in said casing 3, from whence it flows from the outlet 5 after the cap 6 is removed. Obviously such flow will result in the delivery of measured quantities of liquid, for 90 the valve coacting with the cage 8 has a greater or less piston action.

It is to be noted that my improved stopper is of such construction as to make it extremely difficult if not impossible to refill the bottle to which it is applied after the latter has once been emptied; this desirable end being due to the peculiar form and arrangement of valve, seat, and cage structures in combination with the spring and the restricted outlet openings. 100

In some cases the casing 3 and cage structure 8 may be formed as a single integral piece 3^a of glass or porcelain as shown in 110 Fig. 8, in which case the valve seat structure would be held between the top of the

bottle and said piece while the latter would be cemented or otherwise permanently fixed to said bottle. In the structure illustrated the part 3^a has its external surface flush with the outside surface of the bottle neck.

I claim:

The combination with a bottle of a substantially semi-spherical hollow structure extending downwardly into the neck thereof and having a flange resting on the top of said neck, there being a substantially conical opening through the center of said structure; an upwardly extending relatively elongated cage structure having a flange resting on the flange of the seat structure and provided with a substantially cylindrical interior cavity having longitudinally

extending grooves in its walls and a restricted outlet opening at its upper end; a valve having a conical portion co-acting 20 with the seat of the seat structure and a cylindrical portion slidable within the cylindrical cavity of the cage structure; and a spring mounted between the valve and the cage structure; with means for holding said structures to the bottle.

In testimony whereof, I have signed my name to this specification, in the presence of two subscribing witnesses.

HARRY A. KUCERA.
